UNITED STATES PATENT OFFICE

2,149,541

WRENCH

Joseph John Nagle, Philadelphia, Pa.

Application May 10, 1938, Serial No. 207,131

3 Claims. (Cl. 81—126)

This invention relates to an improved wrench and an object of the invention is to provide a wrench having a handle and jaw arrangement of such a character that when leverage is brought to bear upon the wrench handle the jaws will shift towards one another for positively clamping the work therebetween and in a manner to preclude slipping of the wrench.

The invention together with its objects and advantages will be best understood from a study of the following description taken in connection with the accompanying drawings wherein:

Figure 1 is a side elevational view of the wrench.

Figures 2, 3, and 4 are sectional views taken substantially on the lines 2—2, 3—3 and 4—4, respectively, of Figure 1.

Figure 5 is a side elevational view of the wrench with the frame member removed.

Figure 6 is an edge elevational view of one of the jaws.

Figure 7 is an elevation of the jaw end of the wrench showing one type of removable jaw members attached to the regular jaws of the wrench.

Figure 8 is a similar view and showing removable jaw members provided with punching holes in articles.

Figure 9 is a similar view but showing the removable jaws provided with means for cutting a pipe or the like.

Referring to the drawings by reference numerals it will be seen that in accordance with the present invention the wrench embodies a pair of complementary jaws 5 and 6 respectively.

The jaw 5 is formed integral with a shank 7 that at its lower end is laterally enlarged as at 7a and, as shown, is provided with an elongated relatively wide slot 8. In the lower edge thereof the end portion 7a of the shank is provided with a slot 9.

The jaw 6 is provided with an integral shank 10 and at one side of the shank is provided with a rib 11 that has a sliding fit in a groove 12 provided therefor in the shank of the jaw 5 as shown.

The lower portion of the shank 10 is bifurcated to provide a pair of parallel shank extensions 10a, each of which is provided with an oblong opening 13.

Slidable within the slot 8 in the end 7a of shank 7 is a block 14 that is bifurcated to provide a pair of ears 15 between which is pivoted as at 16 the head portion of a handle 17 which has the reduced head portion 17a thereof passing through the slot 9.

The head 17a has a lateral portion 17' working through a slot 20 in the end 7a of shank 7

and in the same edge of the shank in which the groove 12 is formed, and said portion 17' passes between the shank extensions 10a and is provided with the pin 17'' which enters the openings 13.

The block 14 is secured at the desired position of adjustment within the slot 8 through the medium of an adjusting screw 21 that has threaded engagement with the block 14 as shown and works in a slot 22 provided in the edge of 10 the end portion 7a of shank 7 opposite to the aforementioned slot 20.

Block 14 is provided with ribs 23 that are co-operable with transverse grooves 25 provided at one edge of the slot 8 for securing the block 14 15 at the desired position of adjustment when the adjusting screw 21 is threaded home, and as is thought to be apparent.

From the description of the invention thus far it will be seen that an initial adjustment between the jaws 5 and 6 may be made by sliding the jaws relative to one another to position the block 14 at the desired position of adjustment after which the adjusting screw 21 is threaded home to secure the block 14 at the desired position of adjustment. With the jaws 5 and 6 thus properly adjusted the work is placed therebetween and obviously upon application of leverage to the handle 17 jaws 5 and 6 will have a sliding action in reverse directions relative to one another and thereby causing said jaws to move into binding engagement for clamping the work therebetween, with the jaws engaging the work in a manner to preclude slipping of the wrench.

Completing the structure of the wrench is a 35 substantially U-shaped frame 24 which straddles the shanks 7 and 10. The frame 24 is held in position by being fastened directly to the end 7a of shank 7 through the medium of bolts or other fastening elements 25.

Figure 7 shows a pair of removable jaw members 30 removably connected to the jaws 5 and 6, each member 30 including a straight jaw part 31 having teeth 32 on its inner face for engaging the teeth of the jaws 5 and 6, the other face 45 of the part 31 being plain. A curved portion 33 is connected to the outer end of the jaw part 31 to fit over the rounded part of either the jaw 5 and 6 and this part 33 carries a screw 34 for clamping the removable jaw member to a jaw 50 of the wrench. As will be seen from Figure 7 these jaw members 30 provide a smooth flat clamping surface on the jaws 5 and 6 so that the wrench can be used for turning nuts, bolts and the like.

Figure 8 shows one of the jaw members 30' provided with a slot 35 for receiving a member A to be punched and this jaw member has a transverse hole 36 passing therethrough for receiving the punch 37 of the other jaw member 30'. Thus it will be seen that by moving the jaws 5 and 6 toward each other the punch 37 will enter the hole 36 and punch a hole in the member A.

Figure 9 shows the jaw members 30" as being arranged to cut pipes or the like and in this arrangement the member which engages the jaw 5 carries a pair of rollers 38 for engaging the pipe B and the member which engages the jaw 6 carries a pair of roller cutters 39. Thus by moving the jaws 5 and 6 toward each other until the rollers 38 and cutters 39 engage the pipe and then by rotating or oscillating the wrench the cutters 39 will cut the pipe.

Thus it will be seen that with these removable jaw members the wrench can be easily and quickly changed from the construction shown in Figures 1 and 5, the jaw parts of which are provided with teeth, to smooth jaw parts for turning nuts and the like, as shown in Figure 7, or to a device for punching sheet metal and the like as shown in Figure 8 or for cutting pipes and the like as shown in Figure 9.

It is thought that a clear understanding of the construction, operation, utility and advantages of a wrench structure embodying the features of the present invention will be had without a more detailed description.

Having thus described the invention what is claimed as new is:

1. A wrench of the character described comprising a pair of complementary jaws each provided with an integral shank, the shank of one of said jaws having a slot in one end thereof and also provided with a groove in one edge thereof extending lengthwise along the shank from the jaw-equipped end thereof, and the shank of the other of said jaws having a rib on one edge thereof engaging in said groove, a block arranged in said slot, the shank of the first-named jaw also having a slot in one edge thereof, an adjusting screw having a threaded shank portion extending

through the last-named slot and threadedly engaging said block for drawing said block into binding engagement with the first-named shank to secure the block at the desired position of adjustment, and a handle member provided at one end thereof with a head pivotally connected to said block and also having an eccentric connection with the shank of the second-named jaw.

2. A wrench of the character described comprising a pair of complementary jaws each provided with an integral shank, the shank of one of said jaws having a slot in one end thereof and also provided with a groove in one edge thereof extending lengthwise along the shank from the jaw-equipped end thereof, and the shank of the other of said jaws having a rib on one edge thereof engaging in said groove, a block arranged in said slot, the shank of the first-named jaw also having a slot in one edge thereof, an adjusting screw having a threaded shank portion extending through the last-named slot and threadedly engaging said block for drawing said block into binding engagement with the first-named shank to secure the block at the desired position of adjustment, and a handle member provided at one end thereof with a head pivotally connected to said block and also having an eccentric connection with the shank of the second-named jaw.

3. A wrench of the class described comprising a pair of complementary jaws each provided with a shank, the shanks being relatively slidably longitudinally in edge to edge engaging relation, the shank of one jaw having a slot in one end thereof, a block adjustable in said slot, the shank of the other jaw having an edge recess therein, an adjusting screw threaded through the slotted shank into said block for clamping the block to one side of the slot in different adjusted positions, and a handle member provided at one end thereof with a head pivotally connected to said block and having an eccentric connection in the recessed edge of said other jaw.

JOSEPH JOHN NAGLE.
